(57) **CLAIM**

(21) Appl. No.: **29/312,829**

The ornamental design for a component of a liquid treatment device, as shown and described.

(22) Filed: **Nov. 14, 2008**

DESCRIPTION

(51) LOC (9) Cl. 23-01

FIG. 1 is a perspective view of a component of a liquid treatment device showing my new design.

(52) U.S. Cl. **D23/207**

FIG. 2 is a front elevation view thereof, the rear elevation view being a mirror image thereof.

(58) Field of Classification Search D23/207,

FIG. 3 is a right side elevation view thereof, the left side elevation view being a mirror image thereof; and,

D23/209; 210/206; 137/268; 422/264

FIG. 4 is a top plan view thereof.

See application file for complete search history.

Portions of the component of a liquid treatment device not shown in the figures form no part of the claimed design.
